UNITED STATES PATENT OFFICE.

GEORGE B. TOWNSEND, OF RIVER FOREST, ILLINOIS.

DESIGN FOR A CASING FOR MULTIPLE VENDING-MACHINES.

SPECIFICATION forming part of Design No. 37,195, dated October 25, 1904.

Application filed June 30, 1904. Serial No. 214,805. Term of patent 14 years.

To all whom it may concern:

Be it known that I, GEORGE B. TOWNSEND, a citizen of the United States, residing at River Forest, in the county of Cook and State of Illinois, have invented a new and original ornamental Design for Casing for Multiple Vending-Machines, of which the following is a specification.

The drawing is a perspective view of the design for casing for multiple vending-machines of this invention.

What I claim as new, and desire to secure by Letters Patent, is—

The ornamental design for casing for multiple vending-machines as shown.

GEORGE B. TOWNSEND.
